UNITED STATES PATENT OFFICE.

HERMAN H. HEIDBREDER, OF QUINCY, ILLINOIS, ASSIGNOR TO EXCELSIOR STOVE & MFG. CO., OF QUINCY, ILLINOIS, A CORPORATION OF ILLINOIS.

DESIGN FOR A FIREPLACE STOVE OR SIMILAR ARTICLE.

Application filed January 17, 1929. Serial No. 29,651. Term of patent 7 years.

To all whom it may concern:

Be it known that I, HERMAN H. HEIDBREDER, a citizen of the United States, and a resident of the city of Quincy, in the county of Adams and State of Illinois, have invented a new, original, and ornamental Design for a Fireplace Stove or Similar Article, of which the following is the specification, reference being had to the accompanying drawings, forming a part thereof.

In the drawings:

The figure is a perspective view of a fireplace stove showing my new design.

I claim:

The ornamental design for a fireplace stove or similar article as shown.

HERMAN H. HEIDBREDER.
